UNITED STATES PATENT OFFICE.

MATHIAS JOLLY, OF TROY, ASSIGNOR OF TWO-THIRDS TO MARGARET P. THAYER, OF LANSINGBURG, AND MYRTIE E. HART, OF TROY, NEW YORK.

OIL-CAN.

SPECIFICATION forming part of Letters Patent No. 433,244, dated July 29, 1890.

Application filed May 10, 1889. Renewed June 30, 1890. Serial No. 357,184. (No model.)

To all whom it may concern:

Be it known that I, MATHIAS JOLLY, a resident of Troy, in the county of Rensselaer and State of New York, have invented certain new and useful Improvements in Oil-Cans; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in oil-cans; and it consists in the novel construction and combination of parts hereinafter described, and pointed out in the claim.

Figure 1 of the drawings is a central vertical section of my improved can and the enlarged pump-chamber, the pump-tubes being shown in elevation. Fig. 2 is a central vertical section of the pump-tubes. Fig. 3 is a top plan view of the perforated drip-guard detached from the inner side of the perforated can-cover. Fig. 4 is a horizontal section taken on the broken line 4-4 in Fig. 2. Fig. 5 is a side elevation of the pump-plunger detached from the pump-cylinder. Fig. 6 is a central cross-section of the two disks forming the piston, riveted together and detached from the other parts. Fig. 7 is a central vertical section, on an enlarged scale, of the piston-head, guide, concaved valve, valve-stem, and piston-stop fixed thereon detached from the tubes.

The can A is shown provided with a depression or sink A' in its cover, which has a central drip-opening A², and with a pump located near the periphery on one side of the can, having a nozzle A³ projecting over the sink A'. The nozzle is secured to the enlarged chamber-case B, and the case is fixed upon the pump-cylinder B², which is rotary in and movable longitudinally of the tube B³, the tube extending in a fixed position from the top to the bottom of the can, as shown in Fig. 1.

When it is desired to fill a lamp, the nozzle is lifted until the lamp can be deposited in the

sink upon the can-top. The nozzle is then lowered and swung around until it enters the filling-inlet of the lamp, after which the pump is operated to fill the lamp in substantially the manner heretofore employed and well known. 55 The central perforation A² permits any overflow to pass down through and drip into the can. During the transportation of the filled can so perforated the oil is likely to be forced violently out of the perforation unless the same is protected. I provide as such protection a small cap or drip-guard A⁴, which is provided with small perforations A⁵ in the vertical walls of the guard, and may have an attaching-flange A⁶, by which it is soldered to the inner surface of the can-cover, as shown in Fig. 1. 65

The pump piston, which is adapted to slide in the cylinder B² and upon the valve-stem P, has a novel form of construction, is cheaply constructed, and durable. The piston is provided with a central aperture P', made considerably larger than the valve-stem, to receive such stem and at the same time permit of the passage of the desired amount of fluid. I have shown the piston made of two centrally-perforated disks P² and P³, secured to each other by a hollow rivet P⁴, passed through their central perforations, and of a sleeve or piston-guide P⁵, adapted to slide upon the valve-stem. The piston-guide is secured to the piston-head by 70 soldering it to the small upper disk, which may be made of copper, tin, or other material to which solder will readily adhere, while the lower disk P³, which is required to do the work of a piston, may be made of cast-iron or other 75 metal. I have shown the guide secured to the upper disk by a series of downwardly-projecting teeth P⁶, which can be easily soldered to disk P². Any desired number of teeth or arms, as three in the form of a tripod, may 80 be employed.

The valve-stem is provided with the valve P⁷, fixed upon its lower end. This valve is preferably made of a concaved piece of sheet metal adapted to inclose the rivet P⁴ and be seated upon the lower side of the disk to close the central piston-aperture. The stem is also provided with a stop P⁸, fixed thereon, and at its upper end with an operating-handle P⁹, also with the stops P¹⁰ and P¹¹. When the 85 90 95

stem is given a vertically-reciprocating motion, its downward movement brings stop P^8 in contact with the piston-guide, which forces the piston down the cylinder B^2 , the valve occupying the position relatively to the piston shown in Fig. 5, which opens the fluid passage-way P' and permits the fluid to remain in the cylinder. The upward movement of the stem seats the valve upon the piston, which closes P' the piston-aperture and lifts the fluid contained in the cylinder up into the chamber B , from which it is free to run by gravity through nozzle A^3 . The fluid is prevented from following the downward movement of the piston by the check-valve P^{18} in the bottom of the cylinder, which may be any known form of check-valve. The stops P^{10} and P^{12} limit the movements of the valve-stem to short strokes, making it well nigh impossible for the operator to pump the fluid into the chamber B faster than it will run from the nozzle, thereby preventing its running over the top through the stem-aperture. At the same time the operator can easily pump fast enough to keep the chamber filled above the nozzle-outlet, thereby producing a comparatively steady stream of the fluid therefrom.

C is a packing-box secured to the fixed tube

B^3 . This box is filled with packing C' , forming a tight joint around the vertically-reciprocating cylinder B^2 . The box is screw-threaded and adapted to receive the correspondingly-threaded cap C^2 .

I do not claim any invention in the drip-opening and guard.

What I claim as new, and desire to secure by Letters Patent, is—

The combination, in a fluid-can pump, with a concaved valve fixed upon the end of a reciprocatory stem, of a centrally-perforated piston-head formed of two centrally-perforated disks, a hollow rivet inserted in such central perforations to connect the disks with each other and form a central slideway for the valve-stem reciprocatory therein, a piston-guide secured to one of such disks and provided with a central slideway for the stem, and a stop P^8 , fixed upon the stem, substantially as described.

In testimony whereof I have hereunto set my hand this 7th day of May, 1889.

MATHIAS JOLLY.
